UNITED STATES PATENT OFFICE.

WILLIAM M. ANDRUS, OF ALLSTON, MASSACHUSETTS.

CERTIFICATE OF VALUE.

1,359,947.

Specification of Letters Patent. Patented Nov. 23, 1920.

Application filed May 19, 1919. Serial No. 298,114.

To all whom it may concern:

Be it known that I, WILLIAM M. ANDRUS, a citizen of the United States, and a resident of Allston, county of Suffolk, and State 5 of Massachusetts, have invented an Improvement in Certificates of Value, of which the following description, in connection with the accompanying drawings, is a specification, like characters on the drawings representing like parts.

This invention relates to certificates of value and more particularly to bank notes, treasury certificates and the like which circulate generally as currency. The object 15 of the invention is to provide a certificate which can be more readily and conveniently handled in the ordinary course of business, thereby effecting a great economy of time, and one which will be comparatively difficult 20 to tamper with.

As an example of my invention I have here illustrated in a more or less diagrammatic manner a Federal Reserve note for one dollar, and in the drawings:

25 Figure 1 represents one face of this note; and

Fig. 2 is the opposite face, the note being turned end for end as indicated by the letters A, B, C, D, on the corners.

30 The certificate, or note as I will for convenience call it, is of the usual rectangular form and the opposite faces are duplicates so that it is immaterial which side of the note is uppermost, it being equally easy to 35 read either side. The turning over of the note in any way for purposes of inspection, particularly when counting a bundle of notes, is thus obviated and much time is therefore saved.

40 Referring to Fig. 1, each face of the note embodies two portions located upon opposite sides of a diagonal, the diagonal line AC being conveniently marked on the note as a part of the design. On opposite sides of 45 this diagonal are suitable inscriptions which are substantially duplicates, but which are relatively reversely arranged so that if the note is viewed as in Fig. 1, one of the inscriptions is right side up and ready for 50 reading, this preferably being the right hand half of the note, while the other is upside down when the note is viewed in this manner, but on the contrary is right side up if the note is reversed. Thus, in whichever 55 way the note happens to be picked up or held, the complete inscription will be pre-

sented to the view in proper reading position. This effects a saving of fully one half the time now expended by tellers in counting and turning over and around the notes which 60 are received for deposit and by all others who have occasion to handle numbers of notes. Reading of the notes is also facilitated by the diagonal arrangement, since if a bundle of notes is held in one hand by 65 the lower left hand corner and the notes turned by the right hand, substantially the whole inscription in the triangle ABC will be clearly shown by the normal folding back of the corner B.

70 Each of the four inscriptions on the four triangular fields on the two faces of the note may embody the usual validating matter, such as the serial number 3 and seal 5. Herein I have also shown the usual 75 promise to pay 7 and figures denoting the denomination of the note. In the present instance, on each side of the bill at one end, the left hand end in Fig. 1, is a large figure marked with the reference numeral 9, extending practically over the entire end of the triangular field ACD, whereas the opposite end has two small figures, here marked 11, located in a similar position. This serves to prevent "raising" of a note of low value 80 by pasting over the figures with figures cut from a note of higher value, the other part of which will then be presented for redemption, since the smaller figures will not cover over the larger.

90 Conveniently a certain part of the design or inscription is organized on an oblique line about the diagonal dividing the two substantially duplicate inscriptions on the face of the note. Herein I have indicated the 95 redemption clause as being printed in this manner and the diagonal feature may conveniently be emphasized by a frame around this matter. It is a practice at the present time to take a number of notes and divide 100 them lengthwise into narrow strips and then assemble these strips in such a way that one extra note is formed, each of the new notes being somewhat narrower than it should be and each of the old notes contributing a little to the new creation. Of course, in the notes thus reconstructed the designs do not exactly match but when the work is cleverly done the differences are not readily noticed. In the present note, however, there is a strongly emphasized diagonal line which must be broken by any such 105 110

division. The fact that the obliquely organized matter, and in particular the heavily marked diagonal itself, would be broken and the parts out of alinement would be most readily noticed and cause the changed notes to be instantly rejected. An attempt to divide the note parallel to the diagonal would give broken border lines to the note.

As a further protection I may form as a part of each inscription suitable markings herein shown as carets or V's 13 the apices of which rest on one of the diagonals. On the opposite side of the note are complementary markings which when the note is viewed by transmitted light will mate with the markings on the opposite side to form a complete design, as indicated by the dotted lines in the upper left hand corner of Fig. 1 where it will be seen that the mark 13 in full lines adjacent the corner A in Fig. 1 and the mark in full lines adjacent the corner A in Fig. 2 appear as a cross at the diagonal. In the process of reconstructing a number of notes to make an extra one, it is obvious that this marking would be destroyed in some instance or the parts of opposite sides thrown out of alinement. This marking therefore furnishes a means to prevent tampering as well as a means of detecting counterfeiting.

Preferably, as shown, one face of the note is divided along the diagonal AC and the opposite face along the diagonal BD. This not only provides a greater number of checks of the type already described but insures that the triangular fields wherein the writing is right side up will be presented with their bases to the right hand, no matter in what way the note is turned and that this field on which the writing is right side up as regards the observer is on the upper side. This, of course, facilitates the handling and reading of the notes and results in a great saving of time. Since the note is divided diagonally, it is not possible to impose on ignorant persons by cutting apart the duplicate fields of the note since the re-

sulting pieces would not be of the customary rectangular form and furthermore, if the diagonals on opposite faces were oppositely inclined, as here shown, one face would necessarily appear incomplete and mutilated.

The complete series of notes are of the same general design, but I prefer to make the figures indicating value of progressively smaller size as the value of the note increases, as this will prevent the use of figures cut from the notes of higher value to "raise" the notes of lower value, for they will not cover the same over.

Having thus described the illustrative embodiment of my invention here shown and described as an example, what I claim as new and desire to secure by Letters Patent I shall express in the following claims:—

1. A certificate of value having its face divided by a diagonal line into two fields, each field having a complete self-sufficient inscription, the two inscriptions being duplicate but relatively reversely positioned.

2. A certificate of value having four fields bearing substantially similar identifying inscriptions, two fields on one face being on opposite sides of one diagonal and two on the other face on opposite sides of the other diagonal, the inscriptions on each face being relatively reversed.

3. A certificate of value having duplicate faces and on each face substantially duplicate but relatively reversely positioned inscriptions on opposite sides of a diagonal and including markings arranged to mate and form a complete design located at a diagonal when the certificate is viewed by transmitted light.

4. A certificate of value having relatively inconspicuous markings, 13, on opposite faces thereof which when the certificate is viewed by transmitted light mate to form a design.

In testimony whereof I have signed my name to this specification.

WILLIAM M. ANDRUS.
